MEANS FOR SEPARATING FIBERS FROM
BAST PLANTS

James Harold Gillespie, Belfast, Northern Ireland

Application November 28, 1934, Serial No. 755,223
In Great Britain November 29, 1933

8 Claims. (Cl. 19—32)

This invention relates to means for obtaining fiber from flax, or any other fibrous plant, (hereinafter for convenience referred to as flax) and relates to machines in which the flax is separated into pieces, or bundles, clamped in holders and traversed intermittently along rising and falling channels, the traversing movements taking place between rising and falling movements of the channels, the object of the invention being to provide improved means for scutching the plants during vertical movement of the channels.

According to my invention I provide a pair, or a plurality of pairs, of fluted rollers, mounted in suitable bearings, with the rollers placed horizontally and longitudinally with reference to the channel in such manner that the flax depending from the clamp or holder passes between the flutes of the pair or pairs of rollers, the scutching action being only allowed to take place during the descent of the flax and not during its ascent. I may accomplish this in various ways, for example I may mount the rollers on free wheel clutches which permit of the rollers being driven only during the descent of the channel and which disengage the rollers from the drive during the channel's ascent, so that the upward movement of the channel reverses the rollers by the pull of the flax; or the direction of revolution of the fluted rollers may be reversed during the ascent of the channel by a suitable reversing means and gears so that the rollers may revolve during the descending period at a suitable scutching speed, and in the reverse direction at a surface speed equal to the ascending speed of the channel during the ascent. Any other suitable means may be used to ensure the scutching operation taking place during the descent only of the channel and flax and not during the ascent.

The flutes on the rollers may be of any suitable shape or pitch and the rollers may be set to engage the flutes at any suitable depth. Preferably the rollers are so set that the flutes of one roller are equally spaced in the spaces between flutes on the other roller, though they may be otherwise set. The rollers may be driven by suitable gears keyed on in position to ensure this equal, or other, spacing.

It will also be understood that the shape of the various roller flutes and their pitch may be suitably varied to allow of more scutching effect as the flax becomes refined during successive descents as it is passed along the channel.

The invention will now be described, by way of example only, with reference to the accompanying drawings wherein:—

Fig. 1 is a sectional elevation, on the line 1—1 Fig. 2, of a flax scutching machine constructed in accordance with the invention.

Fig. 2 is a corresponding side elevation of a portion of the machine.

Fig. 3 is a complete side elevation to a larger scale of the scutching machine, showing the location of the various rollers and their drives.

Fig. 4 is an elevation, partly in section, of a scutching roller showing the free-wheel device 10 which permits of the roller being driven in one direction and not driven in the reverse direction.

Fig. 5 is a sectional elevation on the line 5—5 Fig. 4.

Fig. 6 is a fragmentary side elevation of a form 15 of reverse gear in which the scutching rollers are positively driven in a reverse direction at a surface speed corresponding to the speed of the ascending flax.

Fig. 7 is an end elevation corresponding to 20 Fig. 6.

Fig. 8 is an end view of the machine showing the usual cam drive for the rising and falling holders.

Referring to the drawings:—

In the example shown in Figs. 1 to 5, the flax scutching machine comprises a preliminary combing sheet 3, two pairs of scutching rollers 1 and 1a and two pairs of beating rollers 2. (The drive and details of sheet 3 are as usual and are omitted.)

The scutching rollers 1 and 1a are mounted on spindles 4 and 4a, the spindles 4 being driven from a shaft 5 by means of chain wheels 6 and 6a and chains 7. The shaft 5 is driven from a

shaft 8 through gear wheels 9 and 10 and change wheel 11, the gear wheel 10 being mounted on a carrier 12 to permit of the change wheel 11 being substituted by a wheel of larger or smaller diameter.

The shaft 8 is driven from a vertical shaft 13 through bevel gears 14 and 14a, the vertical shaft 13 being driven by means of a shaft 15 through bevel gears 16, 16a and 16b. The shaft 15 is driven from a main shaft 17 through bevel gears 18 and 18a (Fig. 3).

The direction of rotation of the vertical shaft 13 is reversed, in synchronism with the rising and falling channel, by means of a sliding dog clutch 19 slidably keyed on the shaft 15 and adapted to engage teeth 19a and 19b on the bevels 16 and 16b, which are loose on the shaft 15. The clutch 19

is moved by means of levers 20 mounted on a horizontal shaft 21, the shaft 21 being oscillated by means of a face cam 22 through the medium of a two armed lever 23 mounted on the shaft 21.

Rollers or followers 24 and 24a are provided on

35

55

the lever 23, the rollers bearing on the face of the cam 22. Cam 22 is mounted on shaft 48 driven in conjunction with the shaft 15 from the main shaft 17. The contour of the face of the cam 22 is arranged so that the clutch 19 engages the teeth 19b on the bevel 16b for a period corresponding to 120 degrees of rotation of the cam 22 thereby rotating the vertical shaft 13 in one direction. The clutch is then disengaged for a period corresponding to 60 degrees of rotation of the cam 22 and then brought into engagement with the teeth 19a on the bevel 16 for a period corresponding to 120 degrees of rotation of the cam 22, thereby driving the vertical shaft 13 in a reverse direction. For the remaining 60 degrees of rotation of the cam 22, the clutch is disengaged. It is to be understood that the periods given are by way of example only and may be varied to suit different circumstances. This series of operations is repeated continuously during the time the machine is in operation.

The scutching rollers 1 and 1a are provided with flutes 25 (see Figs 4 and 5) and the rollers 1a are driven from the rollers 1 through gear wheels 26 and 27. Each of the gear wheels 26 and 27 is composed of a pair of gear wheels such as 26 and 26a, which are bolted together by means of bolts 28 which pass through arcuate slots 28a in the wheel 26 and screw into the wheel 26a, the arrangement being similar for the wheel 27. The curved slots 28a permit of the gear wheels 26 and 27 being moved relatively to each other to adjust the engagement of the flutes 25 in the rollers 1 and 1a, and/or to take up any undesirable backlash in the gears.

To ensure that the rollers 1 are driven only in one direction and are free on their spindles in the reverse direction, a ratchet 29 is provided on each of the spindles 4 which are mounted on roller bearings 30. The chain wheels 6a have each a boss 31 provided with spring loaded pawls 32 which engage the teeth on the ratchet 29. The arrangement is such that the chain wheels 6a drive the spindles 4 in one direction but do not drive them in the reverse direction. The beating rollers 2 are provided with blades 2b and are mounted on spindles 2c (see Fig. 3). The roller pairs 2 are geared together by means of gear wheels similar to those used in connection with the scutching rollers 1 and 1a, but as distinct from the scutching roller the beating rollers 2 are driven continuously in one direction, that is, with the flax-engaging blades going down, from a shaft 33 through chain wheels 34 and 34a, and chain 35. The flax is suspended from holders 36 mounted in a rising and falling channel 37 of the usual type.

In operation, the main shaft 17 rotates the shaft 15 through the bevel gears 18 and 18a. The shaft 15 rotates the clutch 19 slidably keyed thereon, the clutch 19 rotating either of the bevel gears 16 or 16b according as to whether the channel 37 is rising or falling. For example, let it be supposed that it is driving the bevel gear 16 and the channel 37 is moving down for the scutching operation.

The bevel gear 16a is rotated by the bevel gear 16 thereby turning the vertical shaft 13 which in turn rotates the spindle 8 through the bevel gears 14 and 14a. The change wheel 11 mounted on the spindle 8 drives the shaft 5 through the gear wheels 9 and 10, the scutching rollers 1 being driven from the shaft 5 through the chain wheels 6 and 6a and chain 7 at a suitable scutching speed. Just before the channel 37 is about

to ascend, the cam 22 oscillates the shaft 21 through the medium of the lever 23, thereby moving the levers 20 which move the clutch 19 out of engagement with the bevel gear 16. When the channel 37 starts to ascend, the cam 22 oscillates the shaft 21 still further, the levers 20 bringing the clutch 19 into engagement with the teeth 19b on the bevel gear 16b, thereby rotating the shaft 13 in the reverse direction. The shaft 5 is thereby reversed, but the scutching rollers are not rotated in the reverse direction owing to the free-wheel devices on the spindles 4, consequently there is no scutching action on the flax as the channel ascends, the flax merely pulling the rollers 1 and 1a and rotating them in the reverse direction.

In the example shown in Figs. 6 and 7, the reversing motion comprises a vertical shaft 13 driven and reversed as before. The shaft 13 drives the spindle 8 through bevel gears 16 and 16a. On the outer end of the spindle 8 is mounted a change wheel 11 meshing with a gear wheel 10 mounted on a carrier 12 to permit of the diameter of the change wheel 11 being replaced by a wheel of greater or less diameter. The gear wheel 10 meshes with a gear wheel 9 loosely mounted on the shaft 5. The gear wheel 9 is provided with teeth 9a adapted to engage a dog clutch 38 slidably keyed on the shaft 5. Mounted on the spindle 8 is a gear wheel 39 which meshes with a gear wheel 40 mounted on a spindle 40a, and mounted on the spindle 40a is another gear wheel 41 which meshes with a gear wheel 42 loosely mounted on the shaft 5. The gear wheel 42 is provided with teeth 42a adapted to engage the clutch 38. The clutch 38 is moved by means of a bell crank 43 operated through a rod 44 by means of a lever 45, mounted on the shaft 21 which is oscillated by the cam 22 as before. The scutching rollers 1 and 1a are driven from the shaft 5 as before, but the free wheel devices are omitted.

The arrangement just described is such that when the channel 37 is descending for the scutching operation, the clutch 38 is in engagement with the teeth 9a on the gear wheel 9, therefore the shaft 5 is rotated in the direction for rotating the rollers 1 and 1a towards each other at a suitable scutching speed. When the channel 37 starts to ascend, the cam 22 oscillates the shaft 21, thereby moving the lever 45 which operates the rod 44 and bell crank 43, moving the clutch out of engagement with the teeth 9a and into engagement with the teeth 42a on the gear wheel 42, thereby changing the gear ratio for the scutching rollers at a surface speed equal to the speed of the ascending flax, the ratio of the gear wheels 39, 40, 41 and 42 being such as to provide this speed.

Referring to Fig. 8, 46 denotes the usual well known hackling machine gable, and 47 is the lift cam attached to the same shaft 48 to which the cam 22 for controlling the sliding clutch 19 is keyed. The cam 47 controls the rise and fall of the channel 37 by the medium of lever 49, runner 50, link 51, disc 52 attached to the top lift shaft 53, lift pulley 54 also attached to the top lift shaft and belt 55 bolted to the rim of the pulley 54 and to the arch 56 which carries the channel 37 along which the flax holders 36 pass during the scutching process. Reference is made to "The Textile Industries", by William S. Murphy, published by the Gresham Publishing Company, London, 1910, volume 11, pages 9-11, with regard to the type of structure shown in Fig. 8.

As cams 47 and 22 are both keyed to the same

shaft 48, it naturally follows that the cycle of movement of the rise and fall of the channel, and the driving and reversing of the scutching rollers are synchronized.

- 5 I preferably use the well known hackling machine formation for supporting and manipulating the holders, including the well known cross channels with means for screwing and unscrewing, and "pull through" means for repositioning 10 the flax in the holders for treatment of the other end. In this connection I may feed the holders to the machine in pairs, or use holders of greatly increased length, with the object of increasing the production. Where pairs of holders are used I 15 may provide two unscrewing and screwing spindles instead of one as is the present practice, and located, as usual, on the cross channels connecting the two rising and falling channels, I may also provide, in such cases, two "pull through" 20 devices at the changing end of the machines for repositioning the flax in the holders, instead of one device only as at present.

It is to be understood that any other suitable construction may be employed for scutching the 25 flax only during its descent.

Although the description has mainly referred to flax, the same operations may be used for any fibrous plant.

I claim:—

- 30 1. In a machine for obtaining fiber from bast plants including a reciprocable holder for the plants and a pair of rollers having interacting but spaced projections between which the plants are permitted to move lengthwise by the movement of said holder; driving means for the rollers comprising a main driving shaft, two gear trains of different ratios between said shaft and the rollers and clutch means adapted to connect in one or other of said trains in synchronism with the raising and lowering of the holder, the arrangement being that the rollers are driven with a peripheral speed greater than the downward speed of the holder and are rotated in the reverse direction with a peripheral speed equal to the upward speed 45 of the flax.

2. In a machine for obtaining fiber from bast plants including a reciprocable holder for the plants and a pair of rollers having intermeshing flutes between which the plants are permitted to 50 move lengthwise by the movement of said holder; driving means for the rollers comprising a main driving shaft, a reversible gear between the said shaft and the rollers, a unidirectional driving device between said gear and the rollers arranged only to drive the rollers when the holder is descending and means adapted to control said gear in synchronism with the raising and lowering motion of said holder, the arrangement being that the rollers are driven with a peripheral speed 55 greater than the downward speed of the holder and are rotated in the reverse direction merely by the upward withdrawal of the flax.

3. A machine for obtaining fiber from flax straw comprising vertically reciprocable and laterally translatable holders for bunches of the flax, a pair of co-acting fluted rollers between which the bunches are lowered and raised by said holders, driving means for the rollers comprising a main driving shaft, a reversible gear between 60 said shaft and the rollers and a unidirectional driving device between said gear and the rollers arranged only to drive the rollers when the holders are descending, and means adapted to operate said gear in synchronism with the raising 65 and lowering motion of said holders, the arrange- 70

ment being that the rollers are driven with a peripheral speed considerably greater than the downward speed of the holders and are rotated in the reverse direction merely by the upward withdrawal of the flax, a pair of rotary beating elements in alignment with said first mentioned rollers and between which the flax bunches are also raised and lowered and means for driving said beating elements. 5

4. In a machine for removing the woody matter from flax including a vertically reciprocable holder for the flax bunches and a pair of co-acting fluted rollers between which the flax bunches are raised and lowered; driving means for one of said rollers comprising a driving shaft, a reversing gear interposed between said roller and said shaft, means for operating said gear in synchronism with the raising and lowering of said bunch, a unidirectional drive-transmitting device between said gear and said roller and gearing in- 20 terconnecting said roller with the other roller. 10

5. In a machine for removing the woody matter from flax including a vertically reciprocable holder for the flax bunches and a pair of co-acting fluted rollers between which the flax bunches are raised and lowered; driving means for one of said rollers comprising a driving shaft, a double-faced clutch element keyed thereto, a co-operating clutch element at either side of said element, a cam member driven in synchronism 30 with said holders and causing alternate engagement of either face of said clutch, gearing including a change-wheel between said co-operating clutch elements and the driven roller, a unidirectional drive-transmitting device on said 35 driven roller and gearing interconnecting said roller and the other roller. 25

6. A machine for removing the woody matter from flax straw comprising vertically reciprocable and horizontally translatable holders for bunches 40 of said straw, a pair of rollers having intermeshing flutes between which the flax is lowered and raised by the vertical movement of the holders and driving means for said rollers comprising a driving shaft, a double faced clutch element 45 thereon adapted to engage with either of two clutch elements, a first gear train and a second gear train of different ratios between said driving shaft and said rollers and connected respectively to said two clutch elements and cam means 50 driven in synchronism with the raising and lowering of said holders for engaging said double-faced clutch element alternately with either of said two clutch elements, the arrangement being that the rollers are driven at a greater speed 55 than the flax when same is descending and are driven in the reverse direction at the same speed as the flax when the same is ascending.

7. A machine for removing the woody matter from flax straw comprising vertically reciprocable and horizontally translatable holders for bunches of said straw, a pair of scutching rollers having intermeshing flutes between which the flax is lowered and raised by the vertical movement of the holders, a pair of rotary members having intermeshing beating elements in lateral alignment with said scutching rollers, and means for driving said members continuously in the one direction, and driving means for said scutching rollers comprising a driving shaft, a double faced element thereon adapted to engage with either of two clutch elements, a normal gear train including a change-wheel and a reverse gear train of different ratios between said driving 70 75

shaft and said rollers and connected respectively to said two clutch elements and cam means driven in synchronism with the raising and lowering of said holders for engaging said double-faced clutch element alternately with said two clutch elements.

5. For a machine for scutching flax a fluted

scutching roll, comprising a spindle, a drive-receiving element on one end of the spindle, a gear wheel on the other end of the spindle and an adjustable mounting for said gear wheel whereby the same may be angularly adjusted with reference to the flutes.

5
JAMES HAROLD GILLESPIE.
